MORRIS MATTSON, OF NEW YORK, N. Y.

Letters Patent No. 71,775, dated December 3, 1867.

IMPROVEMENT IN APPARATUS FOR HAND AND YOKE-LIFTING.

The Schedule referred to in these Letters Patent and making part of the same.

TO ALL WHOM IT MAY CONCERN:

Be it known that I, MORRIS MATTSON, of the city of New York, in the county of New York, and State of New York, have invented a new and improved Apparatus for Hand and Yoke-Lifting, to increase strength and improve the health; and I do hereby declare that the following is a full, clear, and exact description thereof, and of its mode or manner of operation, reference being had to the accompanying drawings, and to the letters of reference marked thereon, and making a part of this specification.

My invention consists in the construction and arrangement of a new and improved apparatus, suitable for hand and yoke-lifting, or for either, which can be used by the individual desiring to employ the same, without any change in his or her ordinary dress or apparel, and which can be moved from place to place as desired, the apparatus not having or needing to have any fixed connection with the floor or building.

Figure 1 is a general perspective view of the apparatus and its fixed parts.

Figure 2 is a representation of the yoke and its connections for yoke-lifting.

Figure 3 is a vertical section through the lifting-attachments of fig. 1.

Figure 4 shows the apparatus as used in hand-lifting.

Figure 5 shows the same as used in yoke-lifting.

The base or foundation upon which the mechanism or apparatus used for lifting is placed, and to which it is connected, is a platform-scale, A, like those in ordinary use for weighing. The drawings show such a platform-scale with a double scale-beam, $a a'$, one beam having an arm, a'' , with a sliding weight to balance the platform and scales. About centrally with respect to such platform A, and extending through but not touching the same, as shown in fig. 3, is an upright standard, B, which is supported from the frame or foundation C of the scale, or may be attached to any support on which the scale is placed. Such standard connects with the support C by a male and female screw, as shown in fig. 3, which permits the standard to be raised or lowered at pleasure, so as to adapt it readily to individuals of different statures. To such standard B is fixed, above the platform A, a curved or crescent-shaped attachment, $b b$, to which connect the two handles $b' b'$, which may be fixed in one position, or be made to revolve. The crescent $b b$ springs from the standard at a distance of only a few inches above the platform, so as to be easily stepped over, and without disturbing the dress of ladies using the apparatus, and its sides or horns are sufficiently wide apart to allow of persons easily standing between the handles $b' b'$ for the purpose of hand-lifting. Such standard, with its crescent and its handles, or their equivalent, constitute all the mechanism required, in combination with the platform-scale, for hand-lifting. The scale having been balanced by the weight on the arm a'' , the person, male or female, steps upon the platform and takes the position shown in fig. 4, one foot on each side of the crescent. The platform and individual are then balanced by the poise on the beam a' , which also marks the weight of the person on the platform. The standard and handles having been adjusted at the proper height, the handles are grasped, as shown in fig. 4, and the strength tested. The individual standing on the movable platform A which connects with the scale-beam a , but lifting by the handles $b' b'$ against a fixed point, disconnected with the platform, produces a downward pressure on the platform, precisely as though a substance were being weighed, and the force which he expends will be indicated in pounds by the poise on the beam a . There may also be connected with the apparatus any signal as a bell, D, or a flag, which, as the beam rises, will be struck or elevated, and thus indicate to the person exercising, that he has lifted the weight assigned to him. In the arrangement shown in the drawings, as the beam rises, the cross-bar 1 presses against the arm 2, and brings the hammer 3 in contact with the bell, and as the beam descends, the weight 4 draws back the hammer, so as to be acted on by the next motion of the beam.

It will be observed that the position of the arms, while the individual is lifting, is natural, thus allowing not only the easiest but the fullest action to the muscles, and securing the best results therefrom. By the arrangement, also, of the crescent $b b$, rising from the standard B, near to the surface of the platform, the apparatus is not alone convenient for use by men, but ladies can avail themselves of it without any change in their dress, or without disturbing or disarranging the same.

Lifting-apparatus which are in use in some places are constructed with a standard and cross-bar, the latter of which is grasped by the hands in lifting; but such cross-bar is necessarily high enough to be easily reached by the hands, and it is so arranged as to pass between the lower extremities of the person lifting, one hand being thus thrown in front, and the other behind the body. Such position of the hands is not natural,

and consequently the muscles cannot be exercised so freely and efficiently as would be the case if in a natural and unconstrained position. Such an apparatus, when used by women, requires also the putting on of a gymnastic dress, and even then the position of the cross-bar renders its use unpleasant and inconvenient. These objections are wholly remedied by my apparatus, which enables all persons, ladies as well as gentlemen, and also children, to avail themselves of it without change of dress, and without requiring any position of the person or of the limbs objectionable to the most sensitive and delicate individuals.

When the apparatus is to be used for yoke-lifting, a yoke, with its connections, such as is represented in fig. 2, is placed upon the shoulders of the person, connecting with the crescent or standard, and the lifting is from the shoulders, as seen in fig. 5. The yoke E consists of two small metallic plates, d d, one for each shoulder, which are curved or shaped so as to substantially correspond to the form of the shoulders, and are lined with felt or any soft material, so as to rest easily upon the shoulders without causing pain during the exercise of lifting. The metallic plates d d are connected together by an adjustable or sliding bar d', so that they can be placed nearer to or further from each other, according to the breadth of the shoulders of different persons. Over each of the yoke-plates is placed an elongated metallic ring, F, so shaped as not to bear upon or press against the person lifting. These are in contact with the upper side of the yoke-plates d d, and are prevented from slipping therefrom by the notched bar e on such plates. Suitable chains, G, connect such rings with the crescent and standard B, fastening thereto by means of the hooked stem f projecting from the crescent. These chains are of equal length, and have a number of links, g g, of equal size, so that such chains can be equally lengthened or shortened. To render these chains less liable to unhook from the stem f, they may be crossed, as shown in figs. 2 and 5. In yoke-lifting it is, however, desirable to have a rest for the hands, or a support on which the hands can be pressed, and downward pressure exerted by them. This is secured by means of the side standards H H, which rise from the platform A, and the hand-rests I I, the supporting-rods of which slide within the standards H, and are fastened as desired by a thumb-screw, h, so that such hand-rests can be adjusted at different heights, according to different statures of individuals. The sliding parts of such hand-rests should be graduated, so that they can be readily fixed at the same height. At the top of such hand-rests are two or three cross-bars, as seen in figs. 1 and 4, so that the hand can be placed nearer to or further from the body, as desired.

As in the case of hand-lifting, as before described, the lifting by the yoke and shoulder is against or from the standard B, as a fixed point, and the pressure, both by the feet and by the hands, is down upon the platform A, and the strength exercised or amount lifted is measured, as in the former case, by the poise on the scale-beam. In lifting by the hand, the handles b' b' are placed at the side of the person, as shown in fig. 4. In yoke-lifting, these handles may be placed in the same position, or in front of and behind the person, as shown in fig. 5. The latter position I deem preferable.

The mechanism or apparatus hereinbefore described, both for hand and yoke-lifting, may best be combined with a platform-scale, as described and illustrated, as such combination secures an apparatus, as a whole, the most complete and convenient. It will, however, be readily apparent that the adjustable crescent b b for hand-lifting, and by means of which the strength can be exercised, with the arms in a natural position, can be attached to any suitable standard; whether combined with a platform-scale or with any other base of support. The yoke E and the connections may also be used in connection with any lifting-apparatus, and will be found highly convenient and easy in its action.

Differently-arranged apparatus for hand or yoke-lifting than that particularly above described, may also be combined with a platform-scale, securing the advantages of such a combination. The regular and systematic use of such an apparatus will not only greatly increase the strength of the person so using it, but will at the same time invigorate the whole system and improve the general health. Every contraction of the muscles in lifting has the effect of sending the arterial blood more forcibly into them, and of determining the blood also in an increased quantity to the surface of the body and the extremities. In this way, a better circulation is established, the blood is more thoroughly oxygenated, and the health and vitality of the system increased in just that proportion.

What I claim as my invention, and desire to secure by Letters Patent, is—

1. In combination with mechanism or apparatus adapted for hand or yoke-lifting, singly or together, the use and application of a platform-scale, operating substantially as and for the purposes set forth.
2. The application and arrangement, in machines or apparatus for hand and yoke-lifting, of the crescent b b, or its equivalent, with suitable handles b' b', in combination with the standard B, substantially as and for the purposes set forth.
3. So connecting such crescent b b and its standard with any base or support, by a male and female screw, or their equivalent, that the crescent can be raised or lowered, for the purposes set forth.
4. The construction and arrangement of the adjustable yoke E, substantially as and for the purposes set forth.
5. In combination with such a yoke, or its equivalent, the arrangement of the ring F and variable chains G, substantially as and for the purposes set forth.
6. In combination with a yoke, E, for lifting, the arrangement of the adjustable hand-rests I I, substantially as and for the purposes set forth.
7. The combination, with a platform-scale, of mechanism or apparatus for hand and yoke-lifting, singly or together, when constructed as described, and for the purposes set forth.

M. MATTSON.
